UNITED STATES PATENT OFFICE

EARL DANIEL McCADDAM, OF SAN FRANCISCO, CALIFORNIA

AGITATING APPARATUS

Application filed August 13, 1931. Serial No. 556,853.

My invention relates to agitating and mixing apparatus for materials of any kind, although it has been especially designed for concrete aggregates. The invention particularly has for its object to provide certain new and useful improvements in apparatus of the general type disclosed in my copending application, Serial No. 518,817.

Further, the invention has for an object 10 to provide a simple, effective and inexpensive apparatus which includes the receptacle for the materials and agitating and mixing instrumentalities, all arranged as a unit that may be placed in any dump truck body without alteration of the truck body.

Further, the invention has for an object to provide means whereby the aggregate will not pack in corners of the receptacle but all material will be thoroughly and uniformly 20 mixed together by the action of the agitators.

Further, the invention has for its object to provide a mixing and agitating apparatus in which a row of agitators is moved bodily 25 as a unit back and forth from front end to back end of the receptacle (somewhat as a comb), each agitator being rotated on its axis as the movement back and forth occurs.

Further, it is an object to provide a row of 30 (preferably rotatable) agitators arranged as a comb and moved back and forth from end to end of the receptacle, the row being shifted transversely of the receptacle as it reaches the front and back limits of its travel so that the agitators travel in straight parallel lines 35 of twice the number as there are agitators.

Other objects will in part be obvious and in part be pointed out hereinafter.

To the attainment of the aforesaid objects 40 and ends, the invention still further resides in the novel details of construction, combination and arrangement of parts, all of which will be first fully described in the following detailed description, then be particularly pointed out in the appended claims, reference being 45 had to the accompanying drawings, in which:—

Figure 1 is a plan of my invention per se.

Figure 2 is a rear elevation of the same 50 located in a dump truck body, the rear frame bar of the apparatus being broken away and

the dump truck body being indicated in dotted lines.

Figure 3 is a cross section on the line 3—3 of Figure 1.

Figure 4 is an enlarged plan view of the 55 agitator carriage and trolley car unit.

Figure 5 is a side elevation of the same.

Figure 6 is an enlarged detail section of the means for operating the agitators.

Figure 7 is an end elevation of the agitator 60 carriage and trolley car unit.

Figure 8 is an enlarged detail section of the bearing of the driving chain's idler gear and means for attaching same to the rear 65 channel beam.

Figure 9 is an enlarged detail end section of the trolley car unit.

Figure 10 is an enlarged detail cross section of the same, the means of attaching said unit 70 to driving chains is also illustrated.

Figure 11 is an enlarged detail section showing the means for supporting the rack-like channel beam.

Figure 12 is a perspective view of one of 75 the agitators.

In the drawings in which like numerals of reference indicate like parts in all of the figures, 1 represents the rectangular body into which the materials to be treated are put, the body having its inner corners rounded as at 80 2 for a purpose hereinafter explained. 3 represents the tail gate and 4 the discharge spout while 5 indicates the tail gate operating mechanism.

Mounted over and on the body 1 is a rectangular frame consisting of longitudinal I-beams 6, one at each side of the body connected by end transverse I-beams 7 and intermediate cross bars 10—10 at the front, and a channel iron 26 at the back end of the frame. 8 indicates supporting brackets for the frame which serve as legs to space the frame above the body 1 and these brackets or legs 8 are suitably secured to the flange 9 of the body 1 as shown.

11 is the driving motor which may be electrical, internal combustion, or any other suitable motor, and it is connected through a clutch 13 with a reduction gear mechanism 12, the clutch being operated by a device 14 100

of the usual character. The motor 11 and reduction gear mechanism 12 are mounted on the supporting bed 15 carried at the front of the frame. A driving bevelled pinion 16 meshes with a bevelled gear 17 on a driven shaft 18 that is journaled in suitable bearings 19 on the platform or bed 15, and the shaft 18 beneath the bed 15 carries an upper sprocket 20 and a lower sprocket 21.

10 22 is a stub shaft journaled in a suitable bearing 23 beneath the bed 15 and it carries an upper sprocket 20 and a lower sprocket 24. A cross chain 25 passes over the upper sprockets 20—20 so that both sprockets may 15 be driven by the power plant.

Mounted beneath the channel iron 26 and bearing 27 are stub shafts 28 which carry sprockets 29, around which sprockets 29 and around the respective sprockets 21 and 24 20 the two longitudinal chains 30 pass. Each of the chains 30 carries a pin socket 31 hereinafter again referred to.

32 and 33 designate the outer and inner side plates of the trolleys, which plates are 25 spaced apart by sleeves 34 and connected by connecting bolts 35. Each plate also carries a pair of trolley wheels 36 mounted on studs 37 while the outer plates 32 carry bumpers 38 for a purpose presently explained.

30 Connecting the two trolleys are transverse bars 39 spaced apart and having angled ends 40 secured to the outer plates 32 of the trolleys by bolts or cap screws 41. 42 is a sliding bar that is mounted between the bars 39 and is supported by rollers 44 on upper 35 and lower carrying bars 43 that are secured to the sliding bar 42 at its ends as best shown in Figure 10 of the drawings.

The sliding bar 42 carries a set of shaft 40 bearings 45 for the agitator shafts 46, on which the longitudinal agitators 47 are secured in any suitable way, the agitators having any desired number of fingers 48, four being shown for convenience of illustration.

45 Each agitator shaft carries a sprocket 49 and an endless drive chain 50 passes around all of these sprockets. A driving sprocket 51 is also mounted on the central agitator shaft to engage a fixed chain 53 on the periphery or 50 marginal edge of the channel iron 52 which is mounted beneath the cross bars of the frame as a part of the frame, the channel iron 52 having its front and rear ends rounded as shown. The fixed chain 52 serves as 55 a rack member and the sprocket 51 as a pinion member, the purpose of which will presently appear.

There are two guide blocks 54 secured to the slide bar to engage the channel iron 60 52 on the side opposite where the sprocket 51 engages the fixed chain 53 so as to hold the sprocket continuously in mesh with the chain while the agitator car is moving lengthwise of the receptacle or body.

65 Idler sprockets 55 are provided to cooper-

ate with the chain 50 to maintain it in constant mesh with the sprocket 49 of the central agitator.

56 designates supports for the guard and baffle plates 57, which guard and baffle plates 57 are placed over the frame to prevent the material being filled into the body from collecting on the driving chain, etc.

58 represents the dump truck body and 59 75 designates pins on the chain 30 which fit the sockets 31.

Assume the parts to be positioned as indicated in Figure 1 and power being applied to move the trolley car rearwardly. As this motion takes place the left hand agitator will lie close to the left hand side of the body 1 while the right hand agitator will be spaced away from the right hand side of the body 1, all three agitators moving rearwardly as a unit by virtue of the pin 59 and socket 31 connection between the chains 30 and the slide bar 42. As the drive sprocket or pinion member is in mesh with the fixed chain or rack member 53, rotation is imparted to all of the agitators. Now, as the trolley car reaches the rear end of the frame the pin and socket connections will pass around the sprockets 29 and begin to return the car to the forward position. At the same time that the pin and socket connections 59—31 pass around the sprockets 39 the driving sprocket or pinion member 51 will pass around the rear end of the channel iron 52 and in doing so move the slide bar 42 from left to right, thereby bringing the right hand agitator adjacent the right hand wall of the body 1 and the left hand agitator away from the left hand wall of the body 1 as well as moving the central agitator from the left side to the right side of the channel iron 52.

Because of the rounded ends 2 of the body 1 the agitators, while the trolley car is at the end of the frame, will turn in the same proximity to the corners as they do to the side walls of the body 1, thereby preventing dead material forming at the corners of the body.

In order to reduce shock the bumpers 38 are provided to be engaged by the ends of the slide bar or by the members 43 which carry it.

It will be seen that with my construction I have provided a complete unit which may be used as an ordinary mixing tank or be bodily inserted into the body of a dump truck, or it may itself be mounted, as in my other application, directly on the chassis of a dump truck.

By the construction illustrated and described I accomplish with three agitator fingers or tines what would require six to accomplish were the mechanism like that of my prior application.

Further, by giving a rotary motion to the agitators, as well as a rectilinear motion, a more complete mixing and agitating of the material within the receptacle body 1 is ob-

tainable than with apparatus of the prior art with which I am familiar.

From the foregoing description, taken in connection with the accompanying drawings, it is thought the complete construction, operation, and advantages of my invention will be clear to those skilled in the art.

What I claim is:

1. In apparatus of the class described, a rectangular receptacle body, a frame mounted over said body and including a pair of longitudinal tracks located adjacent the sides of said body, a trolley running on each track, spaced cross bars connecting said trolleys to move in unison and constituting therewith a trolley car, endless chains taking over sprockets and extending one adjacent each side of said body parallel thereto, a slide mounted on said cross bars for movement transversely of said body, driving connections between said chains and said slide, means to drive said slide, said cross bars and said trolleys back and forth in the length of said body, and agitators carried by said slide.

2. In apparatus of the class described, a rectangular receptacle body, a frame mounted over said body and including a pair of longitudinal tracks located adjacent the sides of said body, a trolley running on each track, spaced cross bars connecting said trolleys to move in unison and constituting therewith a trolley car, endless chains taking over sprockets and extending one adjacent each side of said body parallel thereto, a slide mounted on said cross bars for movement transversely of said body, driving connections between said chains and said slide, means to drive said chains for moving said slide, said cross bars and said trolleys back and forth in the length of said body, and agitators carried by said slide, said agitators comprising a set of rotatable shafts journaled on said slide, there being one shaft located adjacent either end of the slide, and means for rotating said shafts as said slide is moved.

3. In apparatus of the class described, a rectangular receptacle body, a frame mounted over said body and including a pair of longitudinal tracks located adjacent the sides of said body, a trolley running on each track, spaced cross bars connecting said trolleys to move in unison and constituting therewith a trolley car, endless chains taking over sprockets and extending one adjacent each side of said body parallel thereto, a slide mounted on said cross bars for movement transversely of said body, driving connections between said chains and said slide, means to drive said chains for moving said slide, said cross bars and said trolleys back and forth in the length of said body, and agitators carried by said slide, said agitators comprising a set of rotatable shafts journaled on said slide, there being one shaft lo-

cated adjacent either end of the slide, a fixed rack member parallelling said chains, a pinion member on said slide engaging said rack member, and sprocket and chain connections between said pinion member and said rotatable shafts.

4. In apparatus of the class described, a rectangular receptacle body, a frame mounted over said body and including a pair of longitudinal tracks located adjacent the sides of said body, a trolley running on each track, spaced cross bars connecting said trolleys to move in unison and constituting therewith a trolley car, endless chains taking over sprockets and extending one adjacent each side of said body parallel thereto, a slide mounted on said cross bars for movement transversely of said body, driving connections between said chains and said slide, means to drive said chains for moving said slide, said cross bars and said trolleys back and forth in the length of said body, and agitators carried by said slide, said agitators comprising a set of rotatable shafts journaled on said slide, there being one shaft located adjacent either end of the slide, and means for rotating said shafts as said slide is moved, said body having rounded corners for cooperation with the agitators which are located adjacent the ends of the slide.

5. In a machine of the character described, a rectangular receptacle body, a frame mounted on top of said body and including side I-beams constituting trackage, cross end bars and intermediate cross bars, a platform carried by one end bar and an adjacent intermediate cross bar, a longitudinally disposed center beam carried by said frame and having its ends rounded and its margin provided with a rack member, endless chains and sprockets therefor carried by said frame and extending lengthwise thereof parallelling said center beam, a trolley car running on said trackage and extending transversely of said body beneath said chains and center beam, an agitator carrier mounted on said car for movement from side to side of said body, agitators mounted on said carrier and movable therewith, and driving connections between each chain and said carrier, said agitators including rotating shafts, chain and sprocket means connecting the agitator shafts together, and a driving pinion cooperating with said chain and sprocket means and with said rack member whereby as said endless chains are driven said car will move longitudinally of said body from end to end and said agitator carrier member shifted transversely of the body as it arrives at either end of the body.

6. In a machine of the character described, a rectangular receptacle body, a frame mounted on top of said body and including side I-beams constituting trackage, cross end bars and intermediate cross bars, a platform

carried by one end bar and an adjacent intermediate cross bar, a longitudinally disposed center beam carried by said frame and having its ends rounded and its margin provided with a rack member, endless chains and sprockets therefor carried by said frame and extending lengthwise thereof parallelling said center beam, a trolley car running on said trackage and extending transversely of said body beneath said chains and center beam, an agitator carrier mounted on said car for movement from side to side of said body, agitators mounted on said carrier and movable therewith, and driving connections between each chain and said carrier, said agitators including rotating shafts, chain and sprocket means connecting the agitator shafts together, and a driving pinion cooperating with said chain and sprocket means and with said rack member whereby as said endless chains are driven said car will move longitudinally of said body from end to end and said agitator carrier member shifted transversely of the body as it arrives at either end of the body, said endless chains and said rack member lying in a horizontal plane.

7. In a machine of the character described, a rectangular receptacle body, a frame mounted on top of said body and including side I-beams constituting trackage, cross end bars and intermediate cross bars, a platform carried by one end bar and an adjacent intermediate cross bar, a longitudinally disposed center beam carried by said frame and having its ends rounded and its margin provided with a rack member, endless chains and sprockets therefor carried by said frame and extending lengthwise thereof parallelling said center beam, a trolley car running on said trackage and extending transversely of said body beneath said chains and center beam, an agitator carrier mounted on said car for movement from side to side of said body, agitators mounted on said carrier and movable therewith, and driving connections between each chain and said carrier, said agitators including rotating shafts, chain and sprocket means connecting the agitator shafts together, and a driving pinion cooperating with said chain and sprocket means and with said rack member whereby as said endless chains are driven said car will move longitudinally of said body from end to end and said agitator carrier member shifted transversely of the body as it arrives at either end of the body, a motor on said platform together with power transmitting connections between said motor and said endless chains, and cover and baffle plates over said endless chains and said beam with the rack member and having provisions to discharge material placed on it into said body clear of said endless chains and said beam having the rack member.

EARL DANIEL McCADDAM.

center beam carried by said frame and having its ends rounded and its margin provided with a rack member, endless chains and sprockets therefor carried by said frame and extending lengthwise thereof parallelling said center beam, a trolley car running on said trackage and extending transversely of said body beneath said chains and center beam, an agitator carrier mounted on said car for movement from side to side of said body, agitators mounted on said carrier and movable therewith, and driving connections between each chain and said carrier, said agitators including rotating shafts, chain and sprocket means connecting the agitator shafts together, and a driving pinion cooperating with said chain and sprocket means and with said rack member whereby as said endless chains are driven said car will move longitudinally of said body from end to end and said agitator carrier member shifted transversely of the body as it arrives at either end of the body, a motor on said platform together with power transmitting connections between said motor and said endless chains, and cover and baffle plates over said endless chains and said beam with the rack member and having provisions to discharge material placed on it into said body clear of said endless chains and said beam having the rack member.

EARL DANIEL McCADDAM.

8. In a machine of the character described, a rectangular receptacle body, a frame mounted on top of said body and including side I-beams constituting trackage, cross end bars and intermediate cross bars, a platform carried by one end bar and an adjacent intermediate cross bar, a longitudinally disposed
